UNITED STATES PATENT OFFICE.

EDWARD L. MEGILL, OF BROOKLYN, NEW YORK.

PRINTING-PRESS GAGE.

1,201,846.

Specification of Letters Patent. Patented Oct. 17, 1916.

Application filed February 5, 1915. Serial No. 6,204.

To all whom it may concern:

Be it known that I, EDWARD L. MEGILL, a citizen of the United States, residing at Brooklyn, in the county of Kings and State 5 of New York, have invented certain new and useful Improvements in Printing-Press Gages, of which the following is a specification.

My present invention relates to improvements in what are commonly called feed gages for use on printing presses, and which are secured to the tympan-sheets on the platen of the press to serve as stops or rests, locating the position of the sheets to be 15 printed, so that they may be properly presented to the type. I have in mind particularly the sort of gages in which there is one part that is inserted through a hole or slit in the tympan-sheet, and lies below this 20 sheet, and another part connected to the first part, which overlies the tympan-sheet, the sheet being gripped between these two parts.

One of the objects of the invention is to 25 provide a gage of the kind referred to including a prong which is to be inserted through the tympan-sheet, with means for protecting the fingers of the operator from accidental puncture as may happen when 30 pressure is exerted on the prong in the endeavor to bring the point up through the tympan-sheet after it has been placed below the sheet, and also to prevent the possibility 35 of injury at all times due to the protrusion of the prong point.

Another object of the invention is to provide, in connection with gages which have a prong insertible under the tympan-sheet, means whereby the grip or hold of the device 40 as a whole upon the tympan-sheet is strengthened.

Still another object is to provide a gage of the sort referred to having a part intended to overlie the tympan-sheet and a 45 part that extends beneath the tympan-sheet and protrudes through the sheet at two points, the part beneath the sheet and the part above the sheet being connected together in such a way that the tympan-sheet

is effectually gripped between them, so that 50 movement of the gage relatively to the sheet is minimized.

A further object is to provide a device having the characteristics last-mentioned, with means operative between that 55 portion of the device which lies above the sheet and that portion which lies below the sheet, to vary the grip of said two parts upon the sheet.

Other objects and aims of the invention, 60 more or less broad than those stated above, together with the advantages inherent, will be in part obvious and in part specifically referred to in the course of the following description of the elements, combinations, 65 arrangements of parts, and applications of principles constituting the invention; and the scope of protection contemplated will appear from the claims.

In the accompanying drawings, which 70 are to be taken as a part of this specification, and in which I have shown merely preferred forms of embodiment of the invention, Figure 1 is a top plan view illustrating a gage including my invention, as it appears in 75 place upon a tympan-sheet, a fragment of the latter being shown; Fig. 2 is a sectional view taken on the line 2—2 of Fig. 1, looking in the direction of the arrows; Fig. 3 is a view similar to Fig. 1, illustrating a 80 modified form of embodiment of the invention; Fig. 4 is a view similar to Fig. 1, but with parts broken away, and showing certain of the parts in a slightly different relation from that which they bear in Fig. 81 1; Fig. 5 is a sectional view taken on the line 5—5 of Fig. 3; Fig. 6 is a view similar to Fig. 1 illustrating still another form of embodiment of the invention; Fig. 7 is a side view of the device shown in Fig. 6, 90 showing also in dotted lines one of the positions of the prong 11; Fig. 8 is a view similar to Fig. 1 showing another modification of my invention; and Fig. 9 is a sectional view taken on the line 9—9 of Fig. 8. 95

Referring to the numerals on the drawings and particularly to the forms of embodiment shown in Figs. 1, 2, 3, 4, 5, 6 and 7, I

have indicated at 10 the tympan-sheet of a press, to which my improved gage is shown applied as in use. The gage comprises in each instance a prong part 11 having a 5 pointed end 12 so that it may be readily inserted through the tympan-sheet, making an aperture therein for itself. At its other end this prong part 11 is connected to, or integral with, the usual vertical head portion 10 14, and also connected to, or integral with, this head portion 14 is an upper pressure member comprising two parallel lengths of material, one on each side of the prong portion 11. At their ends opposite to the head 15 portion 14, these upper pressure members 15 may be connected as my means of a bridge 16, as shown in Figs. 1, 2, 3, 4, and 5, or they may be unconnected, as shown in Figs. 6 and 7. It will be understood that the prong 20 member 11 is to be inserted into the tympan-sheet, moved forwardly a desired distance, and then to have its pointed end 12 brought up through the sheet until it protrudes above the same, as shown in Figs. 1, 3, 4 and 5, for 25 instance. The upper pressure members 15 will lie entirely above the tympan-sheet, as shown in the same figures of the drawing, and the sheet is gripped between the prong portion 11 and the upper pressure members 30 15, frictionally, to hold the gage against movement. When the gage is in the desired adjusted position, pressure is applied to the head portion 14, to drive down into the tympan-sheet the points 17.

35 It will be evident that the device thus far described will be effective for the purpose intended, but in order to increase the gripping action between the prong member 11 and the upper pressure members 15, I provide 40 a means operating between the prong member and said upper pressure members. In the embodiments shown, this means takes the form of the ordinary tongue 18; this tongue 18 projects through an opening in the 45 vertical wall of the head portion 14, and bears against the prong part 11. In order that this tongue 18 may cause a reaction between the prong part 11 and the upper pressure members 15, I have shown the tongue member 18 in Figs. 1, 2, 6 and 7, as being 50 provided with lateral offsets or wings 19, which are positioned under the respective upper pressure members 15, and which offset portions 19 have upwardly turned ends 55 20 bearing against the outer edges of the upper pressure members 15, and serving as guides or stops. Likewise, the end of the tongue 18 between the offset portions 19 may be turned upwardly, so as to bear against 60 the inner edges of the upper pressure members 15. It will be obvious from an inspection of Figs. 1, 2, 5 and 7, that as the tongue member 18 is moved toward the left from the position shown in Figs. 1 and 5, the

gripping action between the prong member 65 11 and the upper pressure members 15 will be increased, it being understood of course that the tongue member 18 is bowed about as shown in the drawings. If desired, the upper pressure members 15 may be provided 70 with the slight offsets 21 and 22, which limit the movement of the tongue member 18 in both directions. For the protection of the fingers of the operator, I prefer to provide a guard for the pointed end of the prong 75 member 11. As shown in Fig. 1 this guard may be a simple flattened cap 24, pivoted to one of the upper pressure members 15 and adapted to move from the position shown in Fig. 4, to the position shown in Fig. 1, in 80 which latter position it covers the point 12 of the prong member 11. Aside from its function as a guard, the member 24 positively connects the prong member 11 and the upper pressure members 15, at their rear 85 ends. It has of course been familiar practice to have a prong member below the tympan-sheet and a pressure member or members above the sheet, but these have ordinarily been connected at one end only. By providing for this connection at both ends, and importing into the assembly an independent device (the tongue 18), for varying the gripping reaction between the prong member below the sheet and the pressure members above the sheet I am enabled to secure a 90 better hold of the device, with certain desirable features of adjustability. Furthermore, the guard member 24, when the prong has been inserted far enough under the tympan-sheet, may be pressed down over or in front of the point to bring it up through the sheet, positively bending the point, in place of the old way of bending it up by the un- 95 protected finger of the operator.

100 In Fig. 3, I show a construction in which the adjustment of the tongue member 18 varies the gripping reaction between the prong member 11 and the upper pressure members 15, but instead of providing the tongue member with the offset portions as in Figs. 1 and 5, I make the tongue straight and provide offset portions 25 on the inner edges of the pressure members 15, whereby 110 the tongue 18 is confined between the pressure members 15 and the prong member 11. The function is exactly the same.

115 In Figs. 8 and 9 I have shown a form of gage in which there is a part that lies below the tympan-sheet when in use, and also a part that lies above the tympan-sheet, the sheet being clamped between these two parts. These two parts in this form of embodiment are in the form of plates, the lower plate being indicated by the numeral 27, and 120 the upper plate by the numeral 28. These two plates are connected to, or integral with, 125 the usual head portion 29, having a vertical

wall 30 and a horizontal projection 31, and the tendency is for these two plates to move toward each other. The general form of this style of gage is familiar, but I have 5 provided, by way of an addition or improvement, means for clamping together the otherwise free ends of the two plates. Accordingly, I provide upon one of the plates, in the present instance the lower plate, an ex- 10 tension 32, and upon the other plate, in the present instance the upper plate, a pivoted member 34. In use, after the lower plate has been inserted through an appropriate slit cut in the tympan-sheet, and pushed 15 back to position, another slit is cut in the tympan-sheet, the same being indicated by the reference character 35, and thereupon the pivoted member 34 is moved to the full line position of Fig. 8, so that its free end 20 passes through the slit 35 and under the extension 32 of the lower plate. The result is to clamp the upper and lower plates firmly together, and incidentally to grip the tympan-sheet between them. It may be de- 25 sirable that the pivot member 34 should have more play upon its pivot pin, so that the free end of the pivot member may pass through the slit 35 at a slight angle, in order that it may readily pass beneath the exten- 30 sion 32. This might be provided for by making the pivot pin 36 a screw-threaded stud, and placing a thumb nut upon it above the pivoted member 34. With such a construction the thumb nut could be turned up 35 sufficiently to permit of the necessary play of the pivoted member 34, and after the lat- 40 ter was brought into operative position, as indicated by full lines in Fig. 8, the thumb nut could be tightened down to hold it in position. The general effect is similar to that resulting from the use of the pivoted cap 24 in Figs. 1 and 4.

It will be understood that the various devices described are made of resilient metal, 45 also that sizes and relations of parts are of no importance, except as set out in the claims. As indicating the resiliency characteristic of the prong member 11, I have shown in Fig. 7 an exaggeration of the po- 50 sitions of this prong member when the tongue 18 is at its extreme positions. The dotted line position of the prong member 11 corresponds to the Fig. 1 position of the tongue 18 when it is pushed as far as it will 55 go toward the point 12, in which position the greatest clamping action takes place be- 15 tween the prong member 11 and the upper pressure members.

Inasmuch as many changes could be made 60 in the above construction, and many apparently widely different embodiments of my invention could be made without departing from the scope thereof, it is intended that all matter contained in the above de-

scription or shown in the accompanying 65 drawing shall be interpreted as illustrative and not in a limiting sense.

It is also to be understood that the language used in the following claims is intended to cover all the generic and specific features 70 of the invention herein described and all statements of the scope of the invention which, as a matter of language, might be said to fall therebetween.

I claim:

1. In a device of the kind described, a member adapted to be inserted under a tympan-sheet, an upper pressure member connected to the first-named member and adapted to be positioned over the tympan- 80 sheet, and an element movable to different positions between said two members and bearing against both of them.

2. In a device of the kind described, a member adapted to be positioned under a 85 tympan-sheet, a member adapted to be positioned over the tympan-sheet, and connected to the first-named member, and movable means connected to one of said members and engaging with the side of the other member 90 farthest removed from the first-named member.

3. In a device of the kind described, a prong member adapted for insertion beneath a tympan-sheet, an upper pressure member 95 connected to the prong member and adapted to be positioned above the tympan-sheet, and a guard connected to the upper pressure member and adapted to cover the end of the prong member.

4. In a device of the kind described, a prong member adapted to be inserted beneath a tympan-sheet, upper pressure members connected to the prong member and adapted to be positioned above the tympan-sheet, and a 105 sliding part movable to different positions between the prong member and the upper pressure members and having portions en- gaging both of said pressure members.

5. In a device of the kind described, a 110 prong member adapted to be inserted beneath a tympan-sheet, and parallel upper pressure members connected to the prong member and adapted to overlie the tympan-sheet, said parallel members being connected 115 together at each end.

6. In a device of the kind described, a prong member adapted to be inserted under a tympan-sheet, upper pressure members connected to the prong member and adapted 120 to overlie the tympan-sheet, said parallel members having offset portions on their inner edges, and a member slidable between the prong member and said offset portions.

7. In a device of the kind described, a 125 head member having a vertical wall provided with an opening, a prong member ex- tending from said head member and adapt-

ed to be inserted beneath a tympan-sheet, an upper pressure member extending from the head member in the same direction as the prong member, and a tongue slidable to different positions between the prong member and the pressure member, and extending through the aperture in the vertical wall of the head member.

8. In a device of the kind described, a pair of clamping plates positively connected to-

gether at one end, one of the plates having an extension at the other end, and the other plate having a pivoted member adapted to engage under said extension.

In testimony whereof I affix my signature 15 in presence of two witnesses,

EDWARD L. MEGILL.
